UNITED STATES PATENT OFFICE

HARRY D. FORSE, OF ANDERSON, INDIANA

PRESSING MACHINE

Application filed November 12, 1928. Serial No. 318,774.

This invention relates to a pressing machine suitable for commercial cleaning and pressing establishments.

The chief object of this invention is to simplify and improve pressing machines of the general character hereinafter indicated.

One feature of the invention consists in the treadle construction incorporated with the pressing machine.

10 Another feature of the invention consists in the improved arrangements of the interior of the pressing element and the buck and head may be similarly constructed.

15 The third feature of the invention consists in the adjustment provided for securing predetermined pressure between the buck and head when the treadle is operated to position the head upon the buck.

20 Another feature of the invention consists in the provision of a source of illumination and a control mechanism therefor, and associating the same and the head or a part movable therewith so that the source of illumination is illuminated automatically when the head is in spaced relation with the buck.

25 Another feature of the invention consists in a peripheral enveloping perforated or nozzleled conduit upon the buck or head, or both, which is adapted to cool and dry the garment.

30 The full nature of the invention will be understood from the accompanying drawings and the following description and claims:

In the drawings Fig. 1 is a perspective view 35 of a pressing machine with the head in elevated position relative to the buck. Fig. 2 is a similar view of the pedal and lower part of a modified form of the treadle mechanism shown in Fig. 1 and in the position corresponding to the head engaging the buck.

40 Fig. 3 is a perspective view of the upper rear portion of the pressing machine with the head engaging the buck. Fig. 4 is a top plan view of a pressing member such as the buck with the steam and vacuum chests exposed, the perforated cover and padding being removed. Fig. 5 is a central and longitudinal sectional view through the main frame of the pressing element with the chest and perforated cover nested therein. Fig. 6 is a transverse sectional view taken on line

6—6 of Fig. 4 and of a padded pressing element.

In the drawings 10 indicates a base supporting suitable legs or frame members 11 which are cross connected at their upper ends 55 as at 12. Each side frame member 11 includes an upright extension 13 that terminates in a bearing 14 which pivotally supports shaft 115. Mounted thereon is a pair of lever arms 16, the free and outer ends of 60 which terminate in the supporting member 17. Associated therewith is a handle construction 18, and carried by the plate is a pressing head frame 19. Supported by the ledges 20 of the side frames is a detachable 65 base 21 which supports a pressing buck frame 22, the support being near the end thereof.

Suitably supported, and preferably by one of the lever arms 16 so as to be movable therewith, is a source of illumination including a 70 reflector 23 and a light bulb 24. Current is supplied thereto by the conductors 25 which lead to a switch 26 in turn connected to a master switch 27 supplied by the power line 28. With this arrangement, if the master 75 switch 27 is in closed circuit position, the automatic switch 26 associated with the hinge mounting of the head automatically completes the circuit through the lamp 24 when the head is in the elevated position as shown 80 in Fig. 1. When the head is in the buck engaging position as shown in Fig. 3 the automatic switch opens the circuit to the lamp. When no illumination is desired between the buck and head, the master switch 27 is maintained in the open circuit position, and when thus maintained the automatic switch has no 85 utility. The desirability of the illumination thus automatically provided is obvious.

In addition to the handle 18, a treadle construction is provided for moving the head into engagement with the buck. The two extreme positions thereof are illustrated in Figs. 1 and 2. The base 10 supports a pair of brackets 30 mounting a crank shaft 31 95 which supports a pair of substantially segmental spacing members 32. A flexible sprocket chain 33 (see Fig. 1) or an equivalent strap 133 (see Fig. 2) is secured at one end to each spacer and rides upon the pe- 100

riphery thereof. The peripheral surface of the spacer 32 shown in Fig. 1 is a true arc and is toothed as well. If the spacer were of isosceles triangular shape, the active length of chain, and therefore the lever movement 5 would be relatively the shortest. The spacer 132 shown in Fig. 2 is a true cam and is engageable by strap 133.

The free ends of the chains 33 are connected 10 to a transverse bar or rod 34 secured to a lever 35 which mounts upon its free and exposed end a pedal 36. The opposite end of the lever 35 is mounted upon the rear end of the base 10 by the socketed casing 37, and 15 the other end of the lever supports the similarly socketed pedal 36 forming the treadle construction. The aforesaid arrangement secures oscillation of the intermediate crank portion of shaft 31 when the treadle is operated.

To limit oscillatory movement there is provided a stop 38 covered by rubber cushioning material 138 such as a suitable length of rubber hose. Said stop engages the adjacent bracket 30 when the crank portion of shaft 31 passes through its lowest point of oscillation. The resulting construction is therefore self-locking when it has passed its lowest position. To facilitate release therefrom 20 and initiate return movement past dead center, lever 39, pivotally supported at 40 and provided with tread plate 41 is provided and engages the transverse roller 153 on member 53. Return movement after passing 25 through the lowest point of oscillation is affected by a mechanism hereinafter set forth.

The particular periphery of the segmental member can be of such a nature that any desired type of movement of the head toward the buck can be obtained. For example at the start of the movement of the head 40 toward the buck the actual buck travel might be small for each unit of treadle travel. Likewise after the buck is in motion the intermediate travel thereof might be relatively rapid or large for each unit of treadle travel. Similarly the buck travel can be 45 relatively small for each unit of treadle travel as the buck immediately approaches the head.

A pair of bosses 42 extend inwardly towards each other from each of the lever arms 16 and terminate in spaced relation. Interposed between said arms is a worm wheel 55 43 that is eccentrically mounted upon the shaft 44 and meshes with the worm 45 carried by shaft 46 supporting the hand wheel 47. The shaft 46 is rotatably mounted in 50 the ears 48 formed as extensions of the sides 49 forming a pocket 50 which partially closes the worm wheel 43. The sides 49 constitute an extension of a socket 51 that receives the upper end of connecting rod 52, the lower end 55 of which is receivable by the socketed cast-

ing 53 rotatably supported by the intermediate and crank portion of the shaft 31.

Extending laterally and oppositely from the crank shaft supported socketed end 53 of the connecting rod is a pair of spring supports 54 to each of which is secured one end of an elongated coil spring 55. Each upright extension 13 of the frame supports an inwardly directed slotted bracket 155 through which extends a spring adjusting rod 56. The other end of the spring is suitably connected to said rod. The upper end of each rod is threaded to receive the adjusting nuts 57.

The eccentric worm and worm wheel arrangement provides a self-locking and readily adjustable mechanism for varying the effective length of the connecting rod construction. Through this arrangement predetermined pressure of the head 19 upon the buck 22 can be obtained. The springs 55 are progressively elongated as the head is moved toward the buck. The applied pressure, however, increases as the upper leverage increases, and when the head substantially engages the buck the connecting rod and the crank shaft centers lie in substantial alignment with the rod or slightly off center therefrom. When released therefrom by treadle 41 the springs 55 assist in the return of the head to elevated position. Off center and lowering head movement is limited by cushioned stop 38-138. Upward movement of the head is limited by the connecting rod end 51 engaging the pivot 15 cushioned by rubber hose 115.

The particular interior construction of the pressing member, whether it be the buck or the head, or both, is illustrated in Figs. 4 to 6 inclusive. In said figures, 60 indicates the peripheral outline or side wall of the pressing member, 61 the pressing member bottom wall and 62 the pressing surface. Formed thereby is a heating chamber 63 for heating the entire buck or head. The pressing surface 62 is recessed by an offset and ledge forming inwardly extending wall 64, and the wall 65 therewith closes said opening. This recess nestingly receives the elongated tapered multiple chambered chest construction, including the bottom wall 66 and the exterior side walls 67 which are complementary to the inwardly directed ledge forming walls 64. A plate 68 covers the open face of the chest and includes a plurality of minute perforations 69 which extend therethrough. The cover 68 is secured to the chest as at 70 and the chest is secured to the supporting ledge as at 71.

The chest and cover are aluminum while the support or pressing member body may be cast iron. Aluminum is preferred since it is non-corrosive and the apertures 69 therein will not become clogged and rust.

The chest includes three chambers with

portions arranged in tongue and groove arrangement. One chamber includes a pair of elongated channels 72 in spaced relation with each other but slightly tapered at one end and connected by a cross channel 73. An intermediate and longitudinally extending channel 74 also communicates therewith. Included between the tapered portions of the two parallel first mentioned channels is an elongated chamber having bifurcated channel forming extensions 75 interposed between the three parallel channels 72 and 74. Said bifurcated channels 75 are connected at one end and to another longitudinal channel 77 by cross channel 76. These chambers extend from one end of the chest to substantially the opposite end of the chest. The opposite end of the chest includes the cross channel 79 from the opposite ends of which extend two transverse and tapered channels 78. An inner pair of intermediate and parallel channels 80 communicate therewith through a central chamber 81 and channel 79. The two channels 72 at their remote ends are cross connected or communicate with each other by the lateral passage 82 and this is adjacent the opening 100 so that rapid equalization of pressure obtains. Adjacent the remote end of each channel 72 is an abutment or baffle 101 which serves as a trap to collect steam condensate. The same escapes to chamber 79 through the minute ducts 102 and discharges therefrom through opening 103 adjacent thereto. To prevent pocketing of the condensate, duct 104 connects channel 74 to channel 76, the condensate escaping through opening 105.

In the back the central chamber including the channels 75, 76 and 77 constitute a vacuum chamber and the end chamber including channels 78, 79, 80 and 81 also constitute a vacuum chamber, while the remaining chamber including the elongated channels 72, 73 and 74 constitute a steam chamber. Suitable piping is connected to the respective openings previously indicated for press operation. The vacuum also draws the steam condensate through the ducts 102 and 104.

In the head the two chambers first mentioned are preferably connected so as to form steam chambers while the other chamber constitutes the vacuum chamber. The purpose of the change is to permit but a portion of the head to be supplied with steam and that being the portion in use when short garments are to be pressed.

For control purposes the pressing head is provided with three valve actuating control levers 90 each of which controls one of the chambers and these control levers may be automatically actuated in the movement of the head by extensions of said levers engaging stationary cams carried by the upright extensions 13.

As shown in Fig. 6 each pressing member is covered by a plurality of layers of cushion

material, such as steel wool 91 and the like, a plurality of layers of blanketing material 92, and a canvas cover 93.

Suitably supported at the periphery of each pressing element is a conductor or pipe 94 provided with nozzles 95 that extend into the aforesaid padding construction. These nozzles constitute suction elements and the pipe or conduit 94 is adapted to be connected to a source of vacuum. When thus connected and the control valve therefore (not shown) is actuated, the garment can be readily dried and cooled.

The invention claimed is:

1. In a pressing machine of the character described, the combination of an actuating rod, a crank shaft including a crank portion connected thereto, a segmental spacer rigid with the shaft, a lever, and a flexible connection between said spacer and said lever and having peripheral contact with the spacer whereby lever movement secures shaft movement.

2. In a pressing machine of the character described, the combination of an actuating rod, a crank shaft including a crank portion connected thereto, a segmental spacer rigid with the shaft, a lever, a flexible connection between said spacer and said lever and having peripheral contact with the spacer whereby lever movement secures shaft movement, and yielding means arranged to increasingly oppose continued treadle movement in one direction and decreasingly assist treadle movement in the opposite direction.

3. In a pressing machine of the character described, the combination of an actuating rod, a crank shaft including a crank portion connected thereto, a segmental spacer rigid with the shaft, a lever, a flexible connection between said spacer and said lever and having peripheral contact with the spacer whereby lever movement secures shaft movement, and an adjustable connection for said yielding means for securing predetermined force therefrom.

4. In a pressing machine of the character described, the combination of an actuating rod, a crank shaft including a crank portion connected thereto, a segmental spacer rigid with the shaft, a lever, a flexible connection between said spacer and said lever and having peripheral contact with the spacer whereby lever movement secures shaft movement, the rod and crank connection being movable through the lowest position, and means limiting the movement beyond the lowest position.

5. In a pressing machine, the combination of a pair of pressing elements having relative movement towards and away from each other, a support for one of said elements permitting such movement, an actuating rod connected to said support for moving the same, an adjustable connection between said rod and support for securing predetermined positioning.

of said elements when positioned closest to each other, said connection comprising a pivot on the support, a gear eccentrically mounted thereon and connected to the rod, and a manually adjustable member meshing with the gear for adjusting the same rotatably with respect to the rod.

In witness whereof, I have hereunto affixed my signature.

HARRY D. FORSE.
